UNITED STATES PATENT OFFICE.

CARL JAEGER, OF SEATTLE, WASHINGTON.

ELECTRIC BATTERY.

986,064.

Specification of Letters Patent. Patented Mar. 7, 1911.

Application filed July 13, 1910. Serial No. 571,851.

To all whom it may concern:

Be it known that I, CARL JAEGER, a subject of the Emperor of Germany, and a resident of the city of Seattle, in the county of King and State of Washington, have invented certain new and useful Improvements in Electric Batteries, of which the following is a specification.

The present invention has particular reference to dry cells, and the primary aim thereof is an improved closure for the cell wherein provision is made for introducing fluid to moisten the body.

The invention resides in certain novel features in the construction and arrangement of parts as set forth in the following description and defined in the claims.

In the accompanying drawing, wherein similar reference numerals designate corresponding parts throughout: Figure 1 is a longitudinal section of a cell embodying the features of my invention. Fig. 2 is a transverse section thereof, and Fig. 3 is a perspective of the fluid chamber in broken section.

With reference to Figs. 1 and 2, numerals 3, 4 indicate the two electrodes, with the terminals 4', 5 respectively. 6 is the case or holder, and 7 the filling mass or body which is introduced in a dry state into the case or holder and subsequently moistened when desire to use the cell. Electrode 3 comprises a perforated zinc plate extending in the filling mass or body and held in spaced relations to the electrode 4 and the case or holder by means of disks 3' of comminuted cork.

My improved closure embodies a chamber 8 of variable capacity conveniently comprising telescopic tube section 9 10, and heads therefor, as 9' 10' in which apertures are provided to receive electrode 4. Seated in head 9' is tubular cork 11 whose passage way is normally closed by a glass stopper 12 having a flexible puller 13 attached thereto. Chamber 8 and case holder 6 are preferably

composed of pasteboard suitably paraffined to render it moisture proof.

In closing the cell I place a perforated felt disk or blanket 14 over the filling mass 50 or body and cover the same with a layer 15 of asphalt. Chamber 8, subsequently adjusted to receive when filled the requisite quantity of water or other liquid for moistening the filling mass, is then inserted in 55 the case or holder against the asphalt and covered with a layer 16 of suitable sealing material.

When desired to use the cell, stopper 12 is withdrawn and chamber 8 filled with the 60 moistening liquid. A nail or other pointed instrument is then inserted through the passageway in cork 11 and driven through the bottom head of the chamber and underlying 65 layers of asphalt and felt to provide a channel for leading the liquid to the body of the cell. The stopper is then seated in the cork and the cell is ready for use.

Having thus described my invention, what I claim as new, and desire to secure by Letters Patent of the United States of America, is:

1. In a cell of a dry battery, a liquid holder formed of telescoping sections, one of said sections being provided with a destructible portion, the other of said sections being formed with an opening opposite to the destructible portion of said first section, for the purpose specified.

2. In a cell of a dry battery, in combination with the case thereof, a closure therefor comprising a liquid holder of a destructible nature, and a covering for said closure provided with an opening through which a destroying agent for said closure can be inserted.

3. In a cell of a dry battery in combination with the case, a closure for said case comprising a normally sealed liquid holder, and a perforated felt blanket arranged beneath said closure and having a covering of asphalt.

4. In a cell of a dry battery, in combination with the case, a closure for said case comprising a liquid holder of a destructible nature formed with an opening, a covering seal for said closure, a cork seated in the opening of said closure and projecting through the seal thereof, said cork being formed with a passage-way, a stopper in the

passage-way of said cork, and a flexible puller attached to said stopper. 10

Signed at Seattle, Washington, this 5th day of July 1910.

CARL JAEGER.
